CONTAINER AND RACK FOR HOLDING AND
PRESSING NECKTIES

Smith W. Hoover, Kalamazoo, Mich.

Application September 9, 1950, Serial No. 184,067

8 Claims. (Cl. 38—70)

1

This invention relates to improvements in container and rack for holding and pressing neckties.

The principal objects of this invention are:

First, to provide a container for one or more neckties with a foldable rack that will engage and stretch the ties when the container is closed.

Second, to provide a necktie container with a tie holding rack on which ties may be easily threaded or removed.

Third, to provide a container and rack having the foregoing features which is simple and economical to manufacture yet entirely effective to keep neckties neatly arranged and pressed.

Other objects and advantages of my invention will be apparent from a consideration of the following description and claims.

The drawings, of which there are two sheets, illustrate one preferred form and one modified form of my container and rack.

Fig. 1 is a plan view of a preferred form of my container with the cover removed and with the rack and a necktie positioned therein.

Fig. 2 is a vertical, longitudinal, cross sectional view through the container and rack taken along the plane of the line 2—2 in Fig. 1 and showing the cover of the container associated therewith.

Fig. 3 is a longitudinal, cross sectional view of the container and rack with the rack in unfolded or erected position.

Fig. 4 is a plan view of a modified form of container and rack.

My container and rack are designed to hold the familiar form of elongated four-in-hand neckties, one of which is illustrated at 1. The container comprises an elongated relatively thin box 2, although the thickness of the box is not particularly material. The cover 3 for the box may be entirely separate from the box or hinged thereto as is desired, and in the example illustrated is separable from the box. The box and cover may be made of any suitable permanent or semi-permanent material and I contemplate molding the same from plastic materials.

At one end of the box is provided a pair of inwardly extending bosses or thickened portions 4 which are transversely bored to receive the pintle-like ends 5 of my rack, generally indicated at 6. The rack 6 is conveniently formed by bending wire of a suitable gauge to provide a base cross piece 7 closely adjacent to the pintles 5 and an elongated side member 8 which extends along one side of the interior of the container substantially for the full length thereof. Extending laterally from the side member 8 and spaced from

2

the inner pivoted end of the rack are the inner rack bar 9, outer rack bar 10 and presser bar 11, the latter being positioned on the extreme outer end of the side member. The bent wire type of construction illustrated is convenient in forming these cross bars in that one side of the double wire side bar may be bent into laterally extending loops which form the cross bars. Desirably, the inner rack bar 9 is provided with an inwardly facing hook portion 12 and the outer rack bar 10 is provided with an outwardly facing hook portion 13.

The rack 6 is bowed longitudinally so as to be downwardly concave when folded into the carton. As is most clearly illustrated in Fig. 2, this causes the inner rack bar 9 and outer rack bar 10 to be spaced substantially above the bottom of the box 2 when the presser bar 11 is resting upon the bottom of the box. The under surface of the cover 3 is provided with an inwardly or downwardly extending rib 14 (see Fig. 2) which projects into the box when the cover is closed and bears against the outer rack bar 10 to substantially depress the rack bar and straighten out the rack 6. The compressed positions of the outer rack bar and presser bar are indicated by the dotted lines at 10A and 11A, respectively.

The manner of placing neckties on the rack is most clearly illustrated in Fig. 3 in which the rack is shown in upwardly unfolded or extended position. With the rack thus located, it is a simple matter to fold the necktie once near its middle and slide the fold over the outer rack bar 10 so that the necktie is supported thereby as at 15. The two sides of the necktie are then brought together and threaded between the inner rack bar 9 and the base cross member 7 as is shown at 16 and the ends of the tie are laid out flat in the bottom of the box as shown. It will be appreciated that more than one necktie can similarly be mounted on the rack. After the ties have been placed on the rack and across the bottom of the box, the rack is folded downwardly into the box so that the presser bar engages the end or ends of the tie. When the cover is closed on the box depressing the outer rack bar 10, the presser bar tightly engages the end of the necktie and stretches it longitudinally while the inner rack bar 9 applies an opposite stretching tension to the necktie. The tie is thus placed under substantial tension while being held in flat position and this tension functions to prevent wrinkling of the tie and to straighten out any existing wrinkles while the tie is stored in the container.

In the modified form of a container and rack 55 illustrated in Fig. 4, the box 2A is substantial-

ly the same as the box 2 except that the thickened bosses 4A are positioned along a longitudinal side of the box. The rack 6A is of single wire construction and folds transversely rather than longitudinally into and out of the box. The rack 6A is provided with the same rack bar 9, rack bar 10 and presser bar 11 as in the preferred form of my invention and it will be understood that the rack is desirably bowed longitudinally to function in the same manner as the preferred form of rack. Downward bowing and elongation of the modified rack 6A are accommodated by sliding movement of the pintle portions 5A into the bosses 4A.

Both forms of my container and rack are particularly useful for holding ties in suitcases or luggage while traveling as they prevent wrinkling of the ties. The containers are further useful in conveniently supporting and displaying several ties for selection when the racks are folded out of the boxes.

Having thus described my invention, what I claim as new and desire to secure by Letters Patent is:

1. A necktie carrying case comprising, an elongated box, a cover for said box, an elongated frame of folded wire having one end pivotally mounted within one end of said box and having a longitudinally extending side member positioned along one side of the box, an inner rack bar extending laterally from said side member adjacent the pivoted end of said rack, an outer rack bar extending laterally from said side member and positioned toward the opposite end of said box from said inner bar, and a presser bar extending laterally from the swinging end of said rack and positioned outwardly from said outer bar to engage the bottom of the box closely adjacent the opposite end thereof from said inner rack bar, said rack being substantially bowed in downwardly concave direction, said cover having a depending portion on the under side thereof positioned to engage and depress said outer rack bar when said cover is closed.

2. A necktie carrying case comprising, an elongated box, a cover for said box, an elongated rack of folded wire having a longitudinally extending side member of two wire strands positioned along one side of the box, pintles turned outwardly from said strands and pivoted into the side walls of said box adjacent one end thereof, an inner rack bar extending laterally from said side member adjacent the pivoted end of said rack, an outer rack bar extending laterally from said side member and positioned toward the opposite end of said box from said inner bar, and a presser bar extending laterally from the swinging end of said rack and positioned outwardly from said outer bar to engage the bottom of the box closely adjacent the opposite end thereof from said inner rack bar, said bars being formed by loop extensions of one of said strands, said rack being substantially bowed longitudinally in downwardly concave direction, said cover having a depending portion on the under side thereof positioned to engage and depress said outer rack bar and side member when said cover is closed.

3. A necktie carrying case comprising, an elongated box, a cover for said box, an elongated rack having one end pivotally mounted within one end of said box and having a longitudinally extending side member positioned along one side of the box, an inner rack bar extending laterally from said side member adjacent the pivoted end

of said rack, an outer rack bar extending laterally from said side member and positioned toward the opposite end of said box from said inner bar, and a presser bar extending laterally from the swinging end of said rack and positioned outwardly from said outer bar to engage the bottom of the box closely adjacent the opposite end thereof from said inner rack bar, said rack being substantially bowed in downwardly concave direction, said cover having a portion on the under side thereof positioned to engage and depress said outer rack bar and side member when said cover is closed.

4. A necktie carrying case comprising, an elongated box, a cover for said box, an elongated rack having one end pivotally mounted within one end of said box and having a longitudinally extending side member positioned along one side of the box, an inner rack bar extending laterally from said side member adjacent the pivoted end of said rack, an outer rack bar extending laterally from said side member and positioned toward the opposite end of said box from said inner bar, and a presser bar extending laterally from the swinging end of said rack and positioned outwardly from said outer bar to engage the bottom of the box closely adjacent the opposite end thereof from said inner rack bar.

5. A container for neckties comprising, an elongated shallow box, a rack pivotally mounted within said box and along one end thereof, said rack having a downwardly concave bowed side member positioned to lie along one longitudinal side of said box, a first laterally projecting rack bar secured to said side member adjacent one end of said box, a second laterally projecting rack bar secured to said side member and closer to the opposite end of said box than said one end thereof, and a laterally extending presser bar projecting from said side member closely adjacent said opposite end of said box, said rack bars having hook portions on their ends turned toward the adjacent ends of the box.

6. A container for neckties comprising, an elongated shallow box, a rack pivotally mounted within said box, said rack having a downwardly concave bowed side member positioned to lie along one longitudinal side of said box, a first laterally projecting rack bar secured to said side member adjacent one end of said box, a second laterally projecting rack bar secured to said side member and closer to the opposite end of said box than said one end thereof, and a laterally extending presser bar projecting from said side member closely adjacent said opposite end of said box.

7. A container for neckties comprising, an elongated shallow box, a rack pivotally mounted within said box and along a side thereof, said rack having a downwardly concave bowed side member positioned to lie along said one side of said box, a first laterally projecting rack bar secured to said side member adjacent one end of said box, a second laterally projecting rack bar secured to said side member and closer to the opposite end of said box than said one end thereof, and a laterally extending presser bar projecting from said side member closely adjacent said opposite end of said box.

8. A container for neckties comprising, an elongated shallow box, a rack adapted to be received within said box with at least one end of the rack unconnected to the box and adapted to lie along one end thereof, said rack having a downwardly concave bowed side member positioned to lie along one longitudinal side of said box, a

first laterally projecting rack bar secured to said side member adjacent one end thereof, a second laterally projecting rack bar secured to said side member and closer to the other end thereof, and a laterally extending presser bar projecting from said side member at the said other end thereof.
